John Thomson

UNITED STATES PATENT OFFICE.

JOHN THOMSON, OF BROOKLYN, NEW YORK.

COUNTING-REGISTER.

SPECIFICATION forming part of Letters Patent No. 337,890, dated March 16, 1886.

Application filed April 24, 1885. Serial No. 163,323. (No model.)

To all whom it may concern:

Be it known that I, JOHN THOMSON, of the city of Brooklyn, county of Kings, and State of New York, have invented certain new and useful Improvements in Registers, of which the following is a specification.

This invention refers to registers of that class in which the dial, and also the hands, which indicate sums of units, are caused to rotate together differentially.

The objects of this invention are to simplify and cheapen the construction of the register as a whole, and to insure more accurate and quicker readings from the dial than in instruments of this class heretofore.

In the drawings, Figure 1 is a front elevation. Fig. 2 is a side elevation. Fig. 3 is a detached view of the dial-wheel and pinion; and Fig. 4 is a front elevation similar to Fig. 1, but with the dial represented as having completed half of a rotation.

The dial 5 is fast to the dial-wheel 6. The dial-wheel is journaled on the hub 7 of the follower-wheel 8. On the extension of the said hub 7, which projects through the dial, the hand 9 is secured, and the entire structure rotates upon an axis, as 10, fixedly secured, as in the base-plate 11. In the instance here shown to be assumed, the primary sum of the unit-graduation is one hundred; hence the graduation of the dial and the number of the teeth in the dial-wheel are equal.

In the follower-wheel 8 are formed one hundred and one teeth. Both wheels are actuated by a common driver, as by the pinion 12. Therefore if the relation of the driver to the dial-wheel is such that each unit desired to be registered shall equal one-hundredth part of a rotation of the said dial-wheel, it is clear that any fixed point, as the index 13, will indicate the units, while on the same series of graduations the hand 9 will indicate in sums of one hundred, the latter indication being due to the loss of rotation of the follower-wheel upon the dial-wheel. The sum, then, of the indication of hand 9 will equal the product of 100×100 —namely, 10,000.

The construction and operation as just described is known to be old, and is here stated simply to make clear the manner of obtaining a higher registration in sums of ten thousand.

To effect this in a more simple manner than that shown and described in patent of the United States, dated September 18, 1883, No. 285,322, allowed to me, a pinion or star-wheel, 55 14, is journaled in the dial-wheel, the pivot of which, 15, projects through the dial and carries a hand, 16, which indicates on the integral graduation 17. The sum of this graduation and the number of teeth or spurs in the star-wheel are equal. The star-wheel revolves with the dial-wheel between the said dial-wheel and the follower-wheel.

From the inner face of the follower-wheel projects a pin, tooth, or spur, 18, of such 65 height or length and relatively so located that it will properly engage the star-wheel to rotate the same the space of one tooth during each engagement. Therefore as the follower-wheel will lose but one revolution differentially upon the dial-wheel during a total of one hundred revolutions of the said dial-wheel, and as this will effect a degree of revolution of the star-wheel equal to the space of one of its teeth, the hand 16 will thus register 70 the total sum of the indication of hand 9, and as the sum of the integral graduation 17 here shown is ten, the total reading equals the product of $100 \times 100 \times 10$ —namely, 100,000.

As the engagement of the star-wheel and 80 the tooth which actuates it occurs intermittently but once during one hundred revolutions of the dial, the star-wheel requires sufficient friction to hold against accidental displacement. This may be obtained by a washer, 85 as 22, by friction in the bearing or direct impingement of a spring. This arrangement of the star-wheel on the dial-wheel and the tooth on the follower-wheel to engage the star-wheel comprises the simplest form of an epicyclic- 90 train of gearing, although, as a matter of fact, the actual engagement of the train is intermitting.

For many purposes it is not necessary to register units, sums of ten, and, in more rare 95 instances, sums of one hundred, being sufficiently small. In such instances I simply change the value of the main graduation, marking it 100 or 1,000 where now shown as 10, and so on, when the total readings, respectively, without changing the figures of the integral dial, would equal sums of one mil- 100

lion and ten millions. It is also quite within the limits of practice to double the sum of the integral graduation herein shown and primarily described by simply increasing the 5 number of teeth in the star-wheel.

I claim—

The combination, with the pair of differential gear-wheels and means for operating the same, of the tooth, as 18, the star-wheel 14, to the hand 16, attached to the star-wheel, and

means for indication, as the graduation 17, substantially as described.

In testimony whereof I have signed my name to this specification in the presence of two subscribing witnesses.

JOHN THOMSON.
